MEANS FOR REDUCING MATERIAL

Joseph E. Kennedy, New York, N. Y., assignor, by
mesne assignments, to Reconstruction Finance
Corporation, Philadelphia, Pa., a corporation
of the United States

Application September 7, 1935, Serial No. 39,540

2 Claims. (Cl. 83—10)

This invention relates to the reducing of materials and to crushers of the gyratory type for reducing material, such as ore, rock and the like, and relates particularly to gyratory crushers embodying a conical crushing head supported at one end in a frame concentrically of an annular member or concave, and said head and concave having faces adapted to co-operate to form a crushing chamber, the crushing head being mounted at the end opposite to its support eccentrically of the concave and adapt the head to be gyrated relative to the concave to crush material between the head and concave. In crushers of this character as heretofore constructed the crusher frame comprises separable members including top and bottom members, and a concave supported by an annular member interposed between and directly connected to the top and bottom frame members to constitute a part of the crusher frame.

It is an object of the present invention to eliminate the necessity of this concave supporting shell by arranging the frame members and concave to clamp and support the concave in fixed position between the frame members, and arrange the frame members with means to facilitate the assembling of the frame members and mounting and supporting of the concave between said frame members and mounting the frame members in alinement with each other and take up the force of the crushing pressure on one of the frame members by another frame member.

It has also been the practice in crushers of this character to construct the crushing head separate from the means to support the head in the crusher frame and to mount the head upon a shaft whereby the head is mounted and supported in the crusher frame, and it is another object of the invention to provide a crushing head integral with the support therefor in the crusher frame and to eliminate the use of means to secure the head to its support as well as the labor of machining and mounting of the head on the shaft.

Another disadvantage of gyratory crushers now in use is that lubricant, usually oil, used to lubricate the bearing support for the head carrying shaft in the frame, will drip onto the ore in the crushing chamber causing a deleterious chemical reaction between the oil and amalgam when the crushed ore is treated for the chemical separation of materials therefrom, and it is a further object of the invention to provide means to catch lubricant and prevent dripping of the

lubricant onto the ore as it is crushed in the crushing chamber.

Another object of the invention is to provide a shield carried by the crushing head adapted to co-operate with the usual dust collar or cap encircling the head carrying shaft below the crushing head to form a dust proof chamber that will prevent the passage of dust and fine material to the mounting of the head support in the crusher frame.

A further object of the invention is to facilitate crushing and clearing the crushing chamber of crushed material by providing means connected to a source or supply of liquid and adapted to direct streams of liquid into the crushing chamber between the head and concave.

A still further object of the invention is to provide an improved construction of concave constructed of segments having a continuous and unitary crushing surface.

Heretofore it has been the practice in the reducing of material to bring portions of the crushing face into contact, which resulted in a quick wearing of said parts and a consequent frequent renewal thereof, and it is a further object of the invention to effect a reduction of material without contacting crushing faces for the material and a reduction of the material by impinging a part of the material to be reduced upon another part of such material.

In the drawing accompanying and forming a part of this application.

Figure 1 is a longitudinal sectional view of a crusher taken on the line 1—1 of Figure 2 looking in the direction of the arrows with the base portion broken away and illustrating an embodiment of the invention.

Figure 2 is a cross sectional view taken on the line 2—2 of Figure 1 looking in the direction of the arrows, showing a modified form of concave constructed of segments rigidly secured together to form a unitary structure; and

Figure 3 is a cross sectional view taken on the line 3—3 of Figure 1 looking in the direction of the arrows to show the means for directing streams of fluid into the crushing chamber between the crushing head and concave.

In the embodiment of the invention illustrated in the accompanying drawing, the operative mechanism of the crusher is mounted in and supported by a suitable frame, comprising a pair of superposed axially separable members 4, 11. The lower frame member or shell 4 is arranged to be supported upon a suitable foundation B, and is arranged with a circular chamber in the

upper portion open at the top, said chamber having an annular vertical side wall extending to the top of the frame member and a bottom 4' having an opening therein axially of the frame with a portion 5 declining or extending downwardly in the form of a chute from one side of the chamber to an opening 6 in the side wall of the frame member below the chamber, a tubular portion 7 of said chute extending 10 upwardly and the upper portion extending about the opening in the bottom 4' and constituting a part of a wall or flange 7' extending upwardly from the bottom and about the opening therein. The opening 6 is arranged with a discharge chute 15 8 constituting a continuation of the chute 5. The upper annular end wall of the shell member 4 is arranged with an annular flange 9 extending laterally from the exterior of the shell and below the upper edge of the frame member, said 20 flange reinforcing said annular wall portion of the frame member and forming an annular recess of angular shape in cross section extended into the end and outer face of the annular wall portion. The vertical wall of said recess constitutes a joint surface at the upper end and outer side of the annular wall portion of said frame member for the slidable engagement of a vertical surface of an annular recess 10 of angular shape in cross section extended into the lower 25 end and inner surface of a juxtaposed annular portion 11' of the upper or top frame member 11 of the supporting frame. The top member of the frame is in the form of a spider having an annular wall portion at the end arranged with an 30 annular reinforcing flange 12 extending laterally from the lower end of the annular portion 11', said annular flange corresponding with and to be opposed to the flange 9 of the lower frame member 10, and both flanges having a series of registering perforations for the engagement of securing bolts having retaining and locking nuts threaded onto the end of the bolts projecting below the flange 9, as at 13.

The spider 11 is supported from the lower shell 43 or frame member 4 by an annular crushing member, commonly termed a concave, comprising an annular or ring member 14 of suitable material, such as manganese steel. The outer face of said member is arranged with annular flat face portions diverging from each other intermediate the ends and in a direction toward the opposite ends and the axis of the ring member, as clearly shown in Figure 1, and terminating in spaced relation to each other, as in a circumferential channel 16 intermediate the ends of said ring member. One of said faces is adapted to be engaged with and support the ring member from a corresponding annular face portion arranged on the inner surface of and diverging from the 50 upper end of the vertical annular wall portion of the lower frame member or shell 4 toward the axis thereof, as at 15. The other of said diverging faces of the ring member is adapted to be engaged by a corresponding annular face on the 55 inner surface diverging from the end of the annular portion 11' of the upper frame member 11 toward the axis thereof, as at 17, and whereby the upper frame member is supported from said ring member. It will be obvious that the tightening 60 of the nuts 13 on the bolts will firmly draw the concave to the lower frame member and the upper frame member to the concave. The faces 15, 17 of the frame members 4, 11 diverge from each other toward the axis of the frame member substantially at the same angle as the diverg-

ing outer faces of the concave and are spaced from the end of the frame members, as by annular under cuts or recesses 15' and 17'.

In dismantling the crusher the bolts 13 are removed to permit disengaging and removing the 5 top frame member 11 from the lower frame member or shell and the concave 14.

Due to the drawing of the concave to its supporting face on the lower frame member or shell and the drawing of the top frame member to 10 the concave the lower face of the concave forcibly contacts with its annular supporting face of the lower shell 4. However, the provision of the channel 16 permits of the engagement of an implement of a hoist in said channel and thus facilitates the disengaging and lifting of the concave out of the lower frame member or shell. 15

The inner or crushing surface of the concave is arranged to diverge from intermediate the ends to the opposite ends in a direction outward 20 from the axis of the concave, and in the present instance is effected by arranging said face with two portions 18, 19 diverging from an intermediate portion 20 extending parallelly of the axis of the concave, the crushing face of the concave 25 in conjunction with the crushing face of a conical head 21 forming a crushing chamber tapering downward from the entrance end to the outlet end at a progressively decreasing angle and arranging the crushing chamber with successive 30 crushing zones.

The crushing head 21 is arranged with integral trunnions 22, 22' extending axially from the opposite ends therefrom, the trunnion 22' being slidably mounted in a bushing 23 with an interposed bearing metal 24, such as zinc poured in moltened condition between the trunnion and bushing, the bushing 23 having a spherical shaped portion intermediate the ends whereby it is mounted in a corresponding spherical socket 40 intermediate the ends and eccentrically arranged in a sleeve 25 rotatably mounted in a bearing 26 supported by the bottom shell member 4, the sleeve 25 being adapted to be connected with and rotated from a suitable source of power, not 45 shown, to impart gyratory movement to the head. The opposite trunnion 22 is extended through an opening in a hub 27 integral with the converging ends of the spider 11 and axially of the crusher frame and suspending the head from said hub 50 by a sleeve 28 on the trunnion 22 in a bushing 30 in a portion of the hub bore of increased diameter and engaging upon a bearing ring 29 seated upon the shoulder formed by the hub bore of increased diameter. 55

To yieldingly suspend the head from the supporting sleeve 28 and bearing ring 29 to permit of axial movement of the head, there is provided a flanged collar 31 slidable on the shaft and abutting the supporting sleeve 28 to yieldingly support the head through a series of coiled springs 32 circumferentially disposed about the head trunnion 22 and interposed between the flange of said collar 31 and the flange of a second collar 33 slidable on the outer end of the trunnion 60 22 and retained on the trunnion by a nut 34 screw threaded onto the shaft at the outer side of the collar 33 and the nut locked to the trunnion by a key 35 engaging keyways 36 in the trunnion and nut. The springs 32 are retained 70 in position between the collar 31, 33 by tie rods 37 extended through openings in the flanges of the collars 31, 33 and the springs. The tension of the springs may be varied by screwing the nuts onto or off from the head tie rods 37. This 75

yielding mounting of the head will permit longitudinal movement of the head, as movement of the head in a downward direction against the force of the springs effected by a hard foreign substance, such as scrap iron and the like, that may be accidentally entered into the crushing chamber and permit such foreign substance to pass from between the crushing faces onto the chute 5 without damaging the crushing faces of the concave and head. The springs 32 and the mounting collars 31, 33 may be enclosed by a suitable housing, not shown, engaged over the end of the shaft 22 and supported on a laterally extending flange of a member 35' mounted on the spider hub 23.

The crushing head 21 is of greater length than the concave and the crushing head is normally supported by the springs 32 with the upper end of the head, which is the end of smallest diameter, substantially in the plane of the upper end of the concave, and the end of larger diameter of the head extending below the concave and being of a diameter greater than the greatest diameter of the concave so that the extending portion of the head may be adjusted toward the concave when the lower portion of the head is worn by adjusting the nut 34 after removal of the key 35 to permit moving of the head under the influence of the springs 32. The head is arranged with a crushing face of suitable wear resisting material, such as manganese steel, comprising a mantle 36 encircling and secured to the head by Babbitt metal or zinc poured between the head and mantle in moltened condition through a large space at the juncture of the head with its trunnion 22, as at 37, the head being provided with a shoulder 38 at the lower end thereof to retain the zinc between the head and mantle while in moltened condition. The mantle is further secured on the head, particularly to prevent rotation of the mantle on the head, by an external screw threaded collar 39 engaged on and fixed to the head trunnion 22 by a split ring member 40 engaged on the trunnion below an annular shoulder 41 above the collar 39 and a key 42 engaged in a keyway in the head trunnion and said collar 39 and ring, the key being anchored to the ring by a pin, as clearly shown in Figure 1, the collar 39 retaining the mantle 36 against rotation by a nut 43 screw threaded onto the collar 39 abutting the end of the mantle and having a tongue extended therefrom engaging in a recess in the upper end of the mantle, as shown at 44 in Figure 1, and thus holding the mantle against movement relative to the head.

The crushing face of the mantle 36 is arranged with two angle portions 45, 46 forming an obtuse angle with each other in opposed relation to the intermediate portion 20 of the crushing face of the concave, as at 47, the portion 45 being at the end of smaller diameter and extending at a greater angle than the angle of the portion 46 at the end of the head of larger diameter, and the crushing face of the mantle in conjunction with the crushing face of the concave forming a crushing chamber having successive crushing zones the crushing faces of which are of progressively decreasing angles from the entrance end to the discharge or delivery end thereof, as clearly shown in Figure 1, with a final crushing and sizing zone at the discharge end of the crushing chamber.

By the arrangement of connecting the frame members 4, 11 with the annular reinforcing

flange 12 of the annular portion 11' of the frame member 11 overlapping and embracing the recessed portion of the annular wall of the lower frame member 4 serves to reinforce the portion of the lower frame member to which the greater portion of the stresses of the crushing forces are transmitted through the annular crushing member or concaves. Furthermore, by such arrangement the annular crushing member or concaves are supported directly by the frame members and thus eliminating the carrier heretofore utilized for the concaves to take up the stresses of the crushing forces.

To reduce friction and consequent wearing of the parts, the springs 32, supporting sleeve 28, bearing ring 29 and bushing 30, means are provided to supply lubricant to said parts as by a drip cup carried by the spring suspension enclosing housing, not shown. In the lubricating of said parts in such manner in crushers as heretofore constructed, surplus lubricant drips from the bearing 29 into the crushing chamber onto and mixes with the material being crushed with the result that should the material be ore there might be a deleterious chemical reaction between the lubricant and the amalgam used in the chemical separation of the metals from the crushed ore. To prevent excess lubricant from dripping onto and mixing with the crushed ore, there is provided a lubricant drip collecting cup at the entrance to the crushing chamber, shown in the form of a cylindrical member 48 engaged about and extending upward above the nut 43 and forming therewith an annular receptacle which is adapted to catch lubricant dripping from the bearing 29 or flowing down the head trunnion 22.

It has heretofore been found that in the reducing or crushing of certain materials in dry condition there is a tendency of the material to clog the crushing chamber, and that the wetting or moistening of the material will greatly facilitate crushing of the material and clear the crushing chamber of the material. The wetting of the material is accomplished by a nozzle in the form of an annular conduit 49 mounted to encircle the head trunnion 22 and the bore in the spider hub 27 by brackets 50 fixed to the arms of the spider 11, as clearly shown in Figure 3. To connect the nozzle with a source or supply of liquid, such as water, it is provided with a laterally extending nipple 51 for the connection of a hose or the like leading from the liquid supply. The conduit 49 is provided with a series of perforations 52 extended through the lower face thereof at an angle to the axis of the crusher to direct the streams delivered therefrom in a direction away from the oil receiving receptacle and into the crushing chamber 18 to assure the wetting of the material as it is fed to the crushing chamber and prevent discharge of the water into the lubricant receiving receptacle 48.

To prevent dust and finely reduced material from entering the eccentric mounting of the head trunnion 22', a dust proof chamber is arranged about the portion of the head trunnion extending through the opening in the bottom 4' of the chamber in the upper portion of the lower frame member, and comprising a plate or cap 53 engaged on the head trunnion 22' below the head 21 and supported on the flange 7' extending about the opening in and upward from the bottom 4', and a sleeve or cylindrical member 54 suspended from the bottom of the head by a bracket 55 fixed to the head, as by bolts 56, and connected to the cylindrical member 54, as by welding. The

lower portion of said cylindrical member engages about the peripheral portion of the member 53 whereby the dust and fine material in the discharge chamber of the lower frame member 4 is prevented from passing from said chamber through the opening in the bottom 4' of said chamber to the eccentric mounting of the head trunnion 22' in the bearing 26. The cylindrical member also prevents the accumulating of material discharged from the crushing chamber below the head and directs the material to the delivery chute 5.

To further prevent dust and finely reduced material entering the eccentric bearing, a cap 57 is engaged on the head trunnion below the chute 5 and supported on the upper end of the bearing 26 with a ring 58 of packing material engaged about the head trunnion within an annular flange 59 extending upward from the upper face of the cap 57, a second cap 60 being engaged on the head trunnion 22' in superposed relation to the cap 57, said cap having a downwardly extending peripheral flange 61 and a hub in spaced relation to and of less length than the flange 61 engaged upon and supporting the cap 60 from the packing ring 58.

In Figure 2 there is illustrated a modified structure of the annular crushing member or concave shown in Figure 1, and comprising a series of arcuate segments 63 of suitable material, such as manganese steel, having a cross sectional form similar to that of the solid concave shown in Figure 1 and arranged with the supporting faces 15, 17, channel 16 and crushing face 18, 19, 20. The segments are secured together and to the diverging faces on the annular portions of the top and lower frame members by Babbitt metal or zinc poured in a molten condition between the adjacent side edges of the segments and the diverging faces 15, 17 of the segments and annular portion of the top and bottom frame members, as indicated at 64, the diverging faces of the segments being arranged with recesses 65 to form keyways for the zinc. The segments are united to form an integral concave with a unitary crushing face by bevelling the corners at the juncture of the crushing faces and side edges of the segments and welding the segments together at said bevelled portions, as shown at 66. The constructing of the concave of segments will obviate a great amount of machining which is necessary in a solid ring concave due to the warping of the material thereof during cooling after the concave is cast. The segments are of such a width as to reduce warping and the machining required to a minimum.

The head 21 may be constructed of manganese steel and arranged with the crushing faces 45, 46 thereby eliminating the use of the mantle and the means to secure the mantle to the head.

Having thus described my invention, I claim:

1. In a gyratory crusher, a frame comprising a pair of vertically separable members, each member having an annular connecting wall portion arranged with a laterally extending reinforcing flange to provide a sliding joint connection between said annular wall portions of the frame members with the joint portion of the lower frame member arranged within and reinforced by the flange of the upper frame member, the an-

nular wall portion of each frame member having an inner face portion spaced inwardly from the end of the annular portion and said face portions in the assembled position of the frame members being spaced from each other and diverging in a direction from the axis of the frame members and said face of the annular wall portion of the lower frame member being arranged in opposed relation to the flange thereof, an annular crushing member the opposite end portions of the outer face of which diverge from intermediate the ends in a direction to the opposite ends and axis of said member at substantially the same angle as and adapted to engage and to be supported by the diverging faces of the annular wall portions of the frame members and having an annularly channeled reduced portion between said diverging faces, means engaging the flanges of the frame members to draw the frame members together and the diverging faces of the annular wall portions of the frame members to the diverging outer faces of and secure the annular crushing member in the frame members with the annular member intersecting the connection of the frame members whereby the crushing forces applied to the annular crushing member are adapted to be taken up through the reinforced flange of the annular portion of the lower frame member and connection of the frame members, and a crushing head supported by the frame members to have gyratory movement within the crushing member.

2. In a gyratory crusher, a frame including a pair of vertically separable members, the lower frame member being arranged with a chamber at the upper end having an annular wall and a bottom with a portion thereof declining toward the side of said frame member to constitute a chute to discharge material from the chamber and having an opening axially of the frame member with a flange extending upwardly from the bottom about the opening, and the upper frame member constituting a spider having an annular wall portion adapted to have telescoping connection with and reinforce the annular wall of the chamber of the other frame member, an annular crushing member supported upon and within the connecting annular wall portions of the frame members above the chamber in the lower frame member, a shaft extended through the opening in the bottom of the lower frame chamber and supported in the frame members to have gyratory movement and arranged with a head within and in conjunction with the annular crushing member forming a crushing chamber opening to the chamber in the lower frame member, a disk loosely engaged on the shaft below the head and engaging the flange about the opening in the bottom of the chamber in the lower frame member and closing said opening about the shaft, and a sleeve extended downwardly from the head slightly engaging the peripheral wall of the disk adapted to participate in the gyratory movement of the shaft and operative to direct crushed material discharged into the lower frame chamber away from said flange.

JOSEPH E. KENNEDY.
